CLAIM

The ornamental design for an LED chain link light, as shown and described.

DESCRIPTION

FIG. 1 is a front perspective view of an LED chain link light, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The LED chain link light is shown with a symbolic break in its length. The appearance of any portion of the article between the break lines forms no part of the claimed design.
